CLAIM

The ornamental design for a strain relief for electrical wire, as shown and described.

DESCRIPTION

FIG. 1 is a rear, top, and left side perspective view of a strain relief for electrical wire showing our new design; FIG. 2 is a right elevational view thereof; FIG. 3 is a front elevational view thereof; and, FIG. 4 is a bottom plan view thereof.

The broken line showing of structure is for illustrative purposes only and forms no part of the claimed design.

FIG. 1

FIG. 2

FIG. 3

FIG. 4
